UNITED STATES PATENT OFFICE

ERNST WILCKENS, OF BERLIN, GERMANY

SOUND TRANSMITTING APPARATUS

Application filed June 18, 1928, Serial No. 236,315, and in Germany June 23, 1927.

This invention relates to sound-transmitting apparatus of the diaphragm type, and more particularly to such kind of apparatus operated by means of a gaseous pressure agent.

In the case of the hitherto known senders of this kind the operating agent is introduced from a feed pipe to that particular side of the diaphragm which transmits the sound to the medium either in direct fashion or by means of tuned amplifying chambers. Between the air outlet opening and the air container the pipe dimensions are such that the diameter of the piping is relatively large as compared with the cross-section at the air exit point.

Now in the operation of such senders it has been discovered that the large piping cross-section is an important feature as regards losses in the pipes, while on the other hand the disadvantage exists that the consumption of air is extremely high, making the operation of such apparatus very uneconomical as compared, for example, with electrical transmitters.

It has hitherto been considered desirable in apparatus of the kind in question to allow the operating agent to flow directly into the field of sound. This, however, is not correct, since both by reason of the currents as also the different nature and condition of the active medium and that acted upon disturbances are caused which exercise detrimental action on a proper acoustical effect.

It is the object of the invention to overcome the disadvantages referred to, and this is accomplished by employing a sender or transmitter, in which not the radiating face of the diaphragm, but the side opposite thereto, is acted upon by the inflowing agent. By the provision of a throttling wall in the piping it is also attained that the losses in the pipes remain very small, while on the other hand the sender is not fed with a greater amount of air than is essential for economical operation thereof. The disadvantages arising in conjunction with existing apparatus will be readily apparent to anyone skilled in the art in observing

a sound transmitter of this kind when operated by steam. In this case hot air greatly saturated with particles of water is whirled into still, cool and relatively dry air.

Experiments have hitherto been conducted with many different types of apparatus with a view to generating sound with a small amount of energy. Thus, for example, it has already been proposed to provide chambers in the piping tuned to the sound frequency. In the same manner tuned chambers may also be provided directly against the diaphragm. These measures, however, do not lead to a direct improvement in the efficiency, as the watt-consuming energy remains the same, and merely the so-called idle oscillation energy is reduced; no efficiency, however, is associated with the latter. On the other hand the position is different in the case of the arrangement according to the invention. This arrangement is principally concerned with reducing the watt-consuming, or in other words, the output consuming energy. With the above remarks the invention, which will now be described more fully with reference to the accompanying drawing, will be readily understood.

Fig. 1 shows the principle of the apparatus according to the invention.

Figs. 2 and 3 being modifications.

Referring to Fig. 1, *a* is the diaphragm, which is to transmit sound. For this purpose it is necessary for the same to cause pressure variations in the surrounding medium during vibration of the diaphragm. For attaining the desired vibrations a certain force is required, which is accomplished in the case of senders of the present kind by, with a given operating pressure, a certain pipe diameter at the exit point *b*. In order to utilize this pipe diameter on the one hand independently of the size of membrane or diaphragm and on the other hand the greatest possible movement of the diaphragm for the air outlet point, a plate *d* is mounted at the centre point *e* of the diaphragm. This plate may be furnished with an edge portion or otherwise, as desired.

The plate *d* is situated directly opposite the air outlet *b*. If, for example, the air feed is very strong vibration of the diaphragm will not occur despite the fact that the plate is lifted, since by reason of the strong feed a drop of pressure in front of the plate *d* does not occur. The movement of the diaphragm accordingly remains a constant one, and despite large amounts of air consumed 10 the diaphragm does not emit any sound. If the feed of air is reduced, pressure variations will occur under the plate when a certain amount of air is being introduced, and the diaphragm will accordingly vibrate and 15 emit sound. In this case, however, merely a small proportion of the air flowing through the pipe *b* assists to cause vibration of the diaphragm, and the remainder leaves the sender or transmitter in the manner of direct current, and is to be regarded 20 as a loss. By the fact that a throttle wall having a throttling hole *e* is provided, and furthermore by reason of the fact that the hole *c* is only of such size that all or practically all of the air allowed to pass into 25 the transmitter participates in causing vibration of the diaphragm, it will be readily obvious that a transmitter of the kind described operates with extremely good efficiency, a fact which has also been proved 30 by the experiments conducted. It will also be apparent that due to the provision of the throttling wall entire independency of the size of the feed pipe is achieved, and by 35 proper selection of the size of hole the amount of air introduced into the apparatus may be correctly set.

It has as a matter of fact proved to be most desirable in practice to arrange the 40 throttling wall within the transmitter itself, as independency as regards the piping is then attained to a large degree when the apparatus is being mounted in position.

Fig. 2 shows a modified construction, in 45 which in the case of large diameter of the piping *h* the outlet point *e* possesses a smaller diameter. By reason of the nozzle form any desired arrangement may be selected; thus, for example, a pipe of small diameter, 50 may have a larger diameter at the outlet point.

Fig. 3 shows a modification, in which the air is introduced laterally. The throttling wall is formed by *g*, with the throttle hole 55 *c*. While the medium emerges at *b*, the same is fed to the diaphragm through a movable piping *f*.

It will be readily apparent that also in the case of this embodiment the diaphragm 60 may be furnished with a plate having an edge portion, or also a plate without edge portion.

It will be quite understood that no restriction is made to the actual forms of embodiment shown, but that various other modi-

fications may be made without departing from the spirit of the invention.

What I claim as new and desire to secure by Letters Patent is:

1. A sound transmitting device comprising a diaphragm supported under tension, a pipe conducting pressure fluid from the opposed faces of the diaphragm, a plate supported by the diaphragm but spaced therefrom and adapted to move toward or away from the discharge end of the pipe by varying pressure of the fluid, said plate being of the same diameter as the pipe and of a diameter less than the diaphragm. 70

2. A sound transmitting device as claimed 80 in claim 1, in which the fluid conducting pipe has mounted therein a wall having a throttling opening therein and of a diameter less than the plate.

In testimony whereof I have affixed my 85 signature.

ERNST WILCKENS.
